UNITED STATES PATENT OFFICE.

CHARLES DONAT RICHARD, OF NEW YORK, N. Y.

HOURLY TAXIMETER.

1,269,309.

Specification of Letters Patent. Patented June 11, 1918.

Application filed May 1, 1916. Serial No. 94,769.

To all whom it may concern:

Be it known that I, CHARLES D. RICHARD, a citizen of the Republic of France, residing at New York city, in the county of New York and State of New York, have invented certain new and useful Improvements in Hourly Taximeters, of which the following is a specification.

This invention relates to the general subject of registers, and has particular reference to a novel improvement in that class of devices which are used on motor vehicles to register the total fare due from the passengers carried within a prescribed time limit, and ordinarily known as "taximeters."

To this end the present invention has primarily in view a novel taximeter construction available particularly in connection with the hire of taxicabs, or other motor vehicles, according to a fixed tariff per hour and fraction thereof, or according to other predetermined fixed tariffs that may be prescribed in a municipality. In some localities, for vehicles hired by the hour or for other long periods, the hourly hiring rate is fixed by law. This fixed charge limit is used as the maximum basis for computing the total charge, additional amounts of time in periods of fifteen minutes being reckoned in the total fare recorded by the register.

Accordingly, it will be apparent, that the present invention has in view a register device which clearly distinguishes from the well known taximeter which registers a total fare charge on a calculation of the distance traveled, by providing a device in which the element of time is the controlling factor in the total calculation.

The invention also contemplates a novel construction for carrying the idea, above set forth, into effect, which will be practically foolproof, and relatively simple in operation and structure, which not only renders the maintenance thereof easy and economical, but at the same time provides a device which may be readily handled by the chauffeur of the machine without any attention, other than the operation of a single lever element.

With the above and other objects in view which will appear more clearly as the nature of the invention is better understood, the same consists in the novel combination and arrangement of parts hereinafter more fully illustrated and claimed.

A preferred and practical embodiment of

the invention is shown in the accompanying drawings, in which—

Figure 1 is a perspective view of my invention. 60

Fig. 2 is a front elevation thereof, with the face plate or dial removed and some of the time mechanism also removed to more clearly show the structural features of the device. 65

Fig. 3 is a vertical sectional view taken through one side of the casing and showing in side elevation all of the working parts of the invention. In this view the parts are shown in their normal or neutral position. 70

Fig. 4 is a view similar to Fig. 3, but showing the flag lever of the device turned from its normal neutral position into operative position and also showing all of the parts of the device in their working position. 75

Fig. 5 is a vertical sectional view taken on the line 5—5 of Fig. 3 looking in the direction of the arrows.

Fig. 6 is a top plan view of the invention, the parts being shown in normal or neutral position. 80

Fig. 7 is an enlarged detail view showing the charge regulating device and its relation to the register mechanism, all parts being shown in normal neutral position. 85

Fig. 8 is a view similar to Fig. 7, showing the parts in working position.

Fig. 9 is a horizontal sectional view looking in the direction of the arrows, taken on the line 9—9 of Fig. 8. 90

Fig. 10 is an enlarged detail sectional view showing the disks of the register mechanism in their normal neutral position.

Fig. 11 is a view similar to Fig. 10 showing the register disks in working position. 95

Fig. 12 is a detail sectional view of the cam unit forming a part of the charge regulating device.

Fig. 13 is a detail view showing the relation of the two dollars disks of the register device, whereby a portion carried by the dollars disk of lowest value permits an operating pawl to pick up the dollars disk of higher value at the end of each revolution thereof. 100

Similar reference numerals designate corresponding parts throughout the several figures of the drawings.

As has already been indicated, the present device is intended for, and may be readily called, an hourly taximeter, since it provides for computing the total fare on vehi- 110

cles rented by the hour or fraction thereof, at a fixed tariff per hour. Assuming that the fixed tariff is \$2.50 per hour, the initial charge for the use of a machine will be as 5 stated, then after the hour period is up the device begins to record a charge for each succeeding quarter hour at one-fourth of the hourly rate, for instance \$.60. Therefore, the device in its normal state registers a 10 fixed fare indication of \$2.50, providing, of course, that this is the fixed hourly tariff, and as each quarter hour after the hour period is up the total fare indication will be increased by \$.60.

15 Accordingly, with the ultimate object of computing total fare registration, the present device fundamentally includes in its embodiment three principal mechanisms, viz., a register mechanism, designated generally as 20 R, a time mechanism T, and a charge regulating device C, the latter being thrown into and out of operation with the time mechanism by means of a flag lever F, and the controlling connections therewith. That is to 25 say, the present device includes in addition to the time mechanism T, a register mechanism R including a plurality of independently rotatable registering elements, and a charge regulating device C adapted to 30 actuate the latter an amount prime to the radix including any necessary transfer, as will hereinafter be more fully set forth in detail.

The above mentioned instrumentalities are 35 preferably included in a suitable casing or housing which comprises a supporting member or lock 1, constituting the back wall of the device and a casing section 2 which telescopically receives the mechanism carried by the supporting member 1, and is provided at 40 its front end with a glass window 3 for protecting the face plate 4, which is exposed to the view of the chauffeur and passengers. The lower wall of this casing is preferably provided with an attaching post 5 which depends therefrom and may be supported in a 45 suitable bracket in any convenient position on the vehicle.

The register mechanism R, above referred to, is arranged in the lower part of the casing behind the face plate 4 and essentially includes a plurality of register disks or wheels 6, 7 and 8 having on the peripheries thereof a series of numerals which may be exposed through openings 9 in the face 50 plate 4. As will be observed from Fig. 1 of the drawings these openings are three in number, the two at the extreme left being for the dollars registration, while the one on the right is for the tens of cents registration, the hundredths of cents being always indicated by a naught, which is a fixed quantity. That is to say, the hundredths of cents designation of the present structure is not intended to change in the fare calculations, 55 since the same is on the basis heretofore

pointed out, and this end of the calculation will always end in a naught. For example on the basis of a fixed tariff of \$2.50 for the first hour, and \$.60 for each quarter hour thereafter, the stepping up of the register 70 or counters will show the following numbers, namely, \$2.50, \$3.10, \$3.70, \$4.30, \$4.90. \$5.50, \$6.10, \$6.70, \$7.30, \$7.90, etc. In this connection with the tens of cents disk 6, it may be noted at this point that the series of 75 numerals on the periphery thereof runs 5, 1, 7, 3, 9, 5, 1, 7, 3, 9, while each of the dollars disks 7 and 8 have the numerals on the periphery thereof running in successive order from 1 to 9, inclusive, plus a naught at the 80 end of the series or between the 9 and 1. This arrangement of figures on the disks is made necessary by the peculiar combinations involved on the \$2.50 tariff basis, and of course, may vary where the tariff rate per 85 hour is different. The several disks of the register mechanism are controlled and actuated by suitable register operating means entirely controlled by the charge regulating device C, which is placed in operative and 90 inoperative relation with the time mechanism T by the rotation of the flag lever F.

For the purpose of facilitating the understanding of the invention, reference will now be made to the condition of the several 95 parts when the flag F is in its neutral or normal position, that is, when the part F designated as the flag projects above the casing of the device to signify that the machine is for hire. In this condition the time mechanism, 100 designated generally as T, is intended to be in operation and through a gear G constantly rotates a main driving pinion 10 keyed to a main driving or motion transmitting shaft 11 journaled in the frame work 12 of the 105 clock mechanism. This shaft 11 projects beyond the frame-work 12 and is provided with a squared portion 13 which is adapted to slidably receive a clutch pinion 14 carried by a sleeve 15 engaged by a clutch shifter 110 arm 16 in the conventional manner. This shifter arm 16 is carried by a sleeve 17 loosely mounted on a supporting shaft 18, which latter, in addition to providing a support for the clutch shifting member, constitutes the stem or means for winding the 115 spring of the clock mechanism. To this end the shaft is provided at one end with a winding pinion 19, which meshes with a spring pinion 20, and is provided, at the opposite 120 end, with a winding key 21 exposed at the back of the casing. The sleeve 17 of the clutch shifting member above referred to carries at the end opposite the shifter arm 16, an operating arm 22 which bears against the working face 23 of a controlling cam 24 carried by the end of the flag shaft 25. For the purpose of holding the arm 22 of the clutch shifting member in contact with the working face 23 of the cam, there is prefer- 125 130

ably provided a spring 26 coiled about the shaft 18 and confined between one end of the clutch shifting member and a suitable abutment 27.

5 Accordingly, as will be observed from Fig. 3 of the drawings, when the flag is in neutral position, the cam 24 carried by the shaft 25 is so disposed that the highest portion of its working face holds the arm 22 in such a position, against the tension of the spring 26, that the clutch pinion 14 is out of engagement with the gear 28 of the cam unit U, of the charge regulating device. Thus, when the flag is swung from its normal neutral position, the shaft 25 carrying the cam 24 is rotated and the arm 22 of the clutch shifting member rests in the valley of the cam surface, thus, permitting the clutch pinion 14 carried by the motion transmitting shaft 11 to mesh with the gear 28 of the cam unit, and connecting the time mechanism T with the charge regulating mechanism R.

Referring further to the flag shaft 25, it may be noted that the same carries, in addition to the clutch shifting cam 24, a restraining device and operating cam 29, and a check disk 30, the latter having a ratchet edge 31 for engaging with the spring pressed pawl 32 mounted on the shaft 18. The arrangement of this pawl is such that it engages the ratchet teeth thereof to prevent backward movement of the shaft 25 but permits its free movement in one direction. To prevent the flag shaft 25 from rotating too rapidly in the direction made possible by the pawl and ratchet arrangement, when the flag is pulled down with a sharp thrust, the disk 30 is provided with a plurality of spaced stop lugs 33 projecting from one side thereof. These lugs are preferably four in number and are so arranged that two of them may be engaged at the same time by a brake arm 34, which is loosely mounted on the shaft 18 and pulled downwardly by means of a spring 35. Thus, this braking arrangement is such that the flag shaft is automatically checked at each quarter revolution. In addition to carrying the elements set forth, the shaft 25 also carries between the ratchet disk 31 and the wall 1 of the casing a resetting cam 36, which will hereinafter be more fully referred to.

From the foregoing it will be apparent that in the normal condition of the apparatus the flag is raised and the clutch pinion 14 is out of engagement with the gear 28 of the cam unit U of what is termed herein the charge regulating device, and it is this device that constitutes the operative connection between the time mechanism and the register mechanism. However, when the passenger hires the machine the flag is swung downwardly through an arc of 180 degrees 65 so that the shaft 25 is turned, thus shifting

the clutch pinion 14 on the motion transmitting shaft 11 into mesh with the gear 28, and thereby connecting the time mechanism with the cam unit and starting the latter to move. For a period of one hour the cam unit U, though rotating under the influence of the time mechanism, does not in any way affect the register mechanism R, which exhibits a fixed charge for the hour of \$2.50. However, after the hour is up it is necessary to bring the register mechanism into play to calculate the extra fare for the additional period of use of the machine. The construction of the cam unit U whereby this object is attained, is therefore, such that the register mechanism will not be operated until after the initial hour period is up.

By reference to the drawings it will be observed that this cam unit essentially includes in its organization the operating gear 28, previously referred to, and the register operating cams 37 and 38 rigid with each other and also with said gear. The cam 37 controls the tens of cents register disk 6, and the cam 38 controls the dollars disks 7 90 and 8. These cams are provided with different cam peripheries as will be observed from Figs. 7 and 8, the cam 37 being provided with five teeth a, while the cam 38 is provided with three each designated as 95 b, c, d.

In this connection it should be noted that the two cams 37 and 38 may have any suitable form and arrangement of active elements that will accomplish the desired results, but in the preferable and practical construction these cams are of a pointed or ratchet tooth formation, but the teeth or active elements thereof must maintain a special relation in order to act at irregular intervals, so as to be able to irregularly operate the register disk according to the fixed tariff per hour and quarter hour. The importance of this particular relation between the two cams will be apparent by referring to the schedule of charges involving the stepping up of the register disks for a fixed tariff, for instance \$2.50 at increments of \$.60 each, for every quarter hour after the first hour. In this connection it may be noted by way of example that in stepping up from the charge of \$4.30 to \$4.90, the dollars disk remains inactive while the tens disk steps up from the numerals 3 to 9, but from the charge \$4.90 to \$5.50 both of said register disks and hence both of the cams 37 and 38 operate and these elements also operate at the next step from \$5.50 to \$6.10 whereby this is registered, then the dollars counter and the cam therefor remain inactive while the other cam and the disk controlled thereby operate the counter. From this explanation it will be seen that a critical feature of the machine in order to secure accuracy and practicability is the cam unit 130

of the charge regulating device and the maintenance of a proper set relation between the active elements of the two cams.

The dollars cam member 38 carries there-
5 with a flanged trip collar 39 which is pro-
vided with a clearance notch 40, and to pro-
vide for the simultaneous movement of these
members each of the cam disks and the gear
28 are rigidly connected, and all loosely
10 mounted on the supporting shaft 41 carried
by the frame 12 of the clock work. The
gear 28, mounted on the shaft 41, carries
rigid therewith a resetting pinion 42, and
the latter in turn carries a check disk 43
15 adapted to be restrained by a check pawl
44 for maintaining the entire cam unit in
normal position. This pawl 44 is so ar-
ranged that when in engagement with the
notch of the check disk 43 it prevents the
20 spring-pressed resetting sector 45 from ro-
tating the gear 28 through the pinion 42.
However, it will be understood that the
gear 28 is free to move under power received
from the motion transmitting shaft through
25 the pinion 14 in such a direction that the
pawl 44 will offer no hindrance, and the
last tooth of the resetting sector 45 will
merely trail over the teeth of the resetting
pinion 42.

30 Through the combined efforts of the pawl
44 and the spring-pressed resetting sector
45, the entire cam unit is normally held in
such a position that the clearance notch 40
of the trip collar 39 will be in the position
35 shown in Fig. 7 and after each operation is
automatically returned to normal position
by the sector 45. As the clock mechanism
operates, the gear 28 causes the entire unit
40 to move and thus advance the clearance
notch 40 from its original or initial posi-
tion, so that at the expiration of a period
of one hour the clearance notch is positioned
directly above the trip dog 46 pivotally car-
ried on the angular end 47 of the arm 48
45 of a restraining device D, for maintaining
levers 49 and 50 out of engagement with the
cams 37 and 38, respectively, until after the
hour or predetermined initial period is up.
That is to say, the arm 48, which is a part of
50 the restraining device D is provided with a
laterally projecting restraining arm 51
which holds the charge regulating levers 49
and 50 in such a position that the pawl ends
thereof are out of contact with the cams
55 37 and 38, as will be observed from Fig. 7.
These levers are held in operative position
by the separate springs, x.

This restraining device D which includes
the arm 48, also includes a cam operated arm
60 52 rigidly connected by means of a sleeve
53 with the arm 48. Thus, this sleeve rigidly
unites the arms 48 and 52, so that under
influence of the spring 54 the arm 52 will
be pulled upwardly into contact with the
65 cam 29 on the shaft 25. The shape of this

cam is such that when the flag is in its
normal neutral position the arm 52 is pressed
downwardly, thus causing the arm 48 to be
pressed down and thereby holding the dog
46 carried by the arm 38 beneath the periph-
70 ery of the trip collar 39, and of course the
ends of levers 49 and 50 away from cams 37
and 38. However, when the flag is swung
to its extreme downward position, the crown
75 of the cam 29 releases the arm 52 so the
spring 54 will have a tendency to pull both
arms 48 and 52 upwardly. In thus pulling
the arm 48 upwardly the head of the pivoted
trip dog 46 is pressed against the exterior
75 or periphery of the trip collar 39. In this
position of parts the arm 48, however, is
in substantially the same position it was
when the flag was in neutral position, with
the exception, however, that it is free from
the influence of the cam 29 and could move
80 under the influence of the spring 54 if the
dog 46 were not bearing in the outside of the
collar 39. While the dog is riding on the
external periphery of the collar 39 the levers
49 and 50, which are independent and loosely
85 mounted on the supporting axle 55, like
the sleeve 53, are still held in their extreme
downward position as shown in Fig. 7.
However, when the clock mechanism has ro-
tated the gear 28 for one hour, the clear-
90 ance notch 40 in the collar permits the trip
dog 46 to snap inside of the collar thus re-
leasing the arms 49 and 50 so that their
pawl ends may come in contact with their
respective controlling cams 37 and 38.

100

From the foregoing it will be apparent
that the register mechanism does not come
into play for a period of one hour, or the
entire length of time that the trip dog 46
is traveling on the exterior of the trip col-
95 lar 39. However, as soon as the dog 46
snaps into the clearance notch 40, the reg-
ister operating levers 49 and 50 move into
operative relation with the cams 37 and 38.

105

As the apparatus continues to work with
the trip dog traveling inside of the collar
39, the cam 37 actuates the lever 49 which in
turn actuates the tens of cents disks 6 of the
register mechanism through the link 56.
This link 56 connects as at 57, with the
110 arm 58 pivotally supported at one end on a
shaft 59 extending transversely of the casing
and having at its other end a pivoted pawl
60, the same being controlled by means of a
spring 61 and having its lower end 62 in en-
115 gagement with the ratchet disk 63 carried
by the tens of cents register disk 6.

120

The arm 58 above referred to carries a
spacing sleeve 58^a, and as previously stated
is loosely mounted on the shaft 59. The
125 end of the sleeve 58^a is in close proximity
to a sleeve 64 also mounted on the shaft
59, and carrying rigidly therewith the arms
65 and 66. The arm 65 is connected by a
link 67 with the dollars operating lever 50

130

which is controlled by the cam 38, and any movement imparted by the latter to the arm 65 is imparted to the arm 66 since both arms are rigidly connected by the sleeve 64. Like the arm 58, each of the arms 65 and 66 carry, at one end, a register operating pawl 68 and 69 respectively which are spring tensioned in the same manner as the pawl 60. The lower end of the pawl 68 5 engages with the ratchet disk 70 carried by the dollars register disk 7, and when the arm 50 is actuated by passing over the cam projections on the cam 38, the register disk 7 is moved accordingly. For the purpose 10 of rotating the dollars disk 8 in proper synchronism with 7, that is so that the disk 8 will advance the space of one figure to each complete cycle or revolution of the disk 7, the latter is provided with a smooth 15 hub portion 71 having therein a notch 72. The smooth periphery of the hub 71 during the revolution of the disk 7 prevents the extreme lower end 73 of the pawl 69 from engaging with the ratchet disk 74, 20 carried by the dollars disk 8. When the disk 7 completes a revolution the notch 72 in the hub 71 permits the end 73 of the pawl 69 to engage with one tooth of the ratchet 74, so that upon the upward movement 25 of the pawl the disk 8 will be advanced only one figure and the pawl will then drop out of the notch. On the next movement 79 will slide idly on the smooth 30 periphery of the hub 71.

Therefore, it will be apparent that when the trip dog 46 is riding inside of the collar 39, the levers 49 and 50 are respectively in contact with the working peripheries of the cams 37 and 38, so that a reciprocating 35 motion will be imparted to the ends of the levers 49 and 50, whereby the register disks will be actuated through the links 56 and 57. Upon each downward movement of either of the levers 49 or 50, the pawls 60 and 68 will be pushed downwardly to engage another tooth on the ratchet disks 63 and 70, so that when the levers 49 and 50 are pulled up under the influence of the springs α , the proper register disks will 40 be advanced the correct distance. Obviously, since the tens of cents disk 6 is the most active, it is necessary to provide the cam 37 with more teeth than the cam 38, in the present case the ratio being 5 to 3 for 45 the particular tariff specified. As long as the trip dog 46 is within the collar 39 the disks 6, 7 and 8 will continue to register, and the combined reading will be of the 50 total fare due from the person who hired 55 the machine.

At this point the novel construction of the register device R may be noted. As will be observed from Figs. 10 and 11 each of the register disks 6, 7, and 8 are carried 60 by a shiftable register shaft 75 having

thereon a plurality of aligned offset lugs 76 having inclined ends, one lug being provided for each of the register disks. Each of the said register disks are provided with a hollow hub portion 77, and receive 70 in one end thereof a control bushing member 78 having a spiral or inclined face 79 adapted to bear against the inclined face of the lugs 76 under conditions hereafter explained. These bushings do not extend 75 throughout the length of the hub, but provide a clearance space 80 at one end of the hub in which the lugs 76 freely work, or rather, which permits the disks 6, 7 and 8 to rotate free and loose on the shaft, so 80 that they may be operated by the pawls 60, 68 and 69 when the flag F is in its extreme downward position. In the normal neutral position of the flag F the lugs 76 lie within the slotted portions 81 of the 85 bushing 78, and lock all of the register disks or wheels in their normal position, that is, so that they exhibit the fixed hourly tariff rate. Therefore, since the shaft 75 on which the register disks are mounted is 90 shiftable, when it is desired to bring the meter into use by turning the flag to its extreme downward limit, the shaft 75 may be drawn to such a position that the lugs 76 are in the clearance space 80 at the end 95 of the hubs 77 of the disks.

For the purpose of shifting the shaft 75, the same is engaged at one end by a yoke 82 which is pivoted in the frame work of the device of the apparatus as at 83, and 100 has its end 84 pivotally connected by a link 85 with the lower end of a controlling lever 86. This controlling lever is substantially of right angular formation and is pivoted as at 87 to the back casing or support 1. This angular formation of the lever provides an arm 88 which is caused to follow the periphery of the resetting cam 36 on the shaft 35 by means of a spring 89. The working periphery of the cam 36 is 110 such that in the normal position of the flag F the same presses down on the arm to cause the shaft 75 to be shifted so that the lugs 76 lie in the slots 81 of the bushing 78 and this locks the disks. However, when 115 the flag is in its extreme downward position the cam 36 is of such shape that the spring 89 is permitted to act and cause the yoke arm to swing on its pivot 83 and pull the shaft out so that the lugs 76 may work 120 in the clearance 80 of the hubs 77 of the disks.

In view of the particular construction of the bushings 78 and the lugs 76 it will be apparent that the lugs will reset the disks 125 when the flag is moved from its extreme downward position back to its normal position, since the inclined face of the lug 76 will engage the inclined faces of the bushings 78 when the shaft 75 is pushed inward 130

by the return of the flag to its normal position and the reverse of the operation described above. This feature is of material importance in the invention since it provides for accurately bringing the register disks back to the fixed hourly tariff rate, regardless of their position when the passenger leaves the machine.

In order to prevent backward movement of the register disks 6, 7 and 8 during the operation of the device, each ratchet 63, 70, and 74 carried by the disks 6, 7 and 8 is preferably engaged by a spring pressed check pawl 90 suspended from a shaft 91 arranged transversely the casing at the front of the apparatus.

For the purpose of informing the occupant of the machine that the device is in use or not in use, the face plate 4 of the device may be provided with the semicircular windows 92 and 93, behind which operate the pivotally supported recording disks 94 and 95, respectively having thereon "Recording" and "Not recording". Each disk is provided with a pinion 96 at the rear side thereof, and is pivotally supported in the frame work 12 of the clock mechanism. The said pinion 96 of each disk is adapted to mesh with a controlling sector 97 carried by a shaft 98 journaled in the frame as at 99 and carrying at the end opposite its connection with the sector 97 an arm operating the arm for the disk 94 being designated as 100 while the arm for the disk 95 is marked 100'. This arm 100 is controlled by means of a spring 101, and is moved or shifted by means of a cam post 102 carried by the cam disk 24 on the flag shaft 25. When the flag is in its normal neutral position the cam post 102 will not engage either of the levers 100 or 100' as shown in Fig. 3, and the arrangement is such that the black parts of both dials 94 and 95 are visible through the apertures of the front face plate 4. When the flag is driven 90° the post 102 will move the lever 100 and thereby move the dial 94 into such a position that the word "Recording" will appear through the aperture 92 as shown in Fig. 1. However, when the flag is driven 180° from neutral position, the black part 94 again appears before the opening 92, since the post 102 has left the lever 100. Then, upon the turning of the lever from the 180° position to the 270° position, the post 102 engages lever 100' to thus bring the portion of dial 95 having thereon "Not recording" before the aperture 93, thus indicating that the mechanism is being thrown out of use. As the flag lever moves from 270° position back to normal neutral position, the post 102 leaves lever 100' so that the black portion of the dial 95 is again exposed before the aperture 93 to indicate the normal state of the apparatus. Thus the invention provides for informing the passenger of the

state of the machine, so that if he does not see the figures register for one hour he will know that the device is in operation.

To keep an accurate record of the total amounts collected by the driver of the machine, and the number of times his taximeter has been in use during his period of service, suitable counters or recorders of well known construction may be employed in connection with the register mechanism R and charge regulating mechanism C. The counter associated with the register mechanism R is designated as 103, while the counter associated with the charge regulating mechanisms C is designated as 104. Both of these counters are suitably mounted on the rear wall of the casing 1, and are visible respectively through suitable apertures (not shown) and in the rear wall 1 of the device.

Referring now particularly to the counter 103 associated with the registering device R, it will be observed that the same is provided with an operating pinion 107 which is adapted to mesh with a gear sector 108 rigidly carried by the arm 58 journaled in the shaft 59. It will be remembered that the arm 58 is the one which operates the tens of cents register disk 6, and is actuated by the lever 49 through the link 56. Thus, any reciprocating motion imparted, through the connections just referred to, through the arm 58 or sleeve 58^a, are transmitted to the sector 108, which is in mesh with the gear 107 of the counter. Thus, each time the arm 58 reciprocates, due to the lever 49 passing over the surface of the cam 37, the lever 107 will be moved to operate the counter, which is of the conventional reciprocating type. Every time the arm 107 moves to register a \$.60 fare, its movement will be registered on the counter 103. Therefore, if at the end of the day, it is found that the counter registers "50", for example, it can be easily computed that the total fares registered by the device is \$32.50. That is to say, since there were fifty reciprocations of the sector 107, and consequently fifty movements of the disk 6, the total of this calculation would be \$30.00. Then, since the original charge was \$2.50, the \$30.00 registered for the total quarter hours, plus the initial charge would give the total sum of \$32.50.

Now to inform the inspector or like party as to how many times during the day the machine has been used and therefore should register a \$2.50 fee, the counter 104 is utilized. This counter is provided with a lever 109 rigid on the end of its shaft which is pivotally connected as at 110 with a link 111 which is connected at its upper end with the lever 52 which forms a part of the restraining device D. As stated in connection with the specific description of the latter device, when the device is in its normal neutral position the cam 29 on the shaft 25 presses the

lever 52 down, and when the flag is turned down into working position, the lever 52 rises under the influence of its spring because the cam 29 is such that it does not bear 5 on the lever when the flag is down. When the service period of the meter is over and the operator swings the flag back to neutral position the cam 29 again presses the arm 52 down causing the link 111 to move in the 10 opposite direction. Thus, the reciprocating motion is imparted to the link 111 each time the device is used. This reciprocating movement is transmitted to the lever 109 on the shaft of the counter to thus cause the same 15 to operate and register once. Therefore, every time the device is brought into service the counter 104 will record the same. If the meter has been in use ten times during the day for a period of less than one hour, the 20 register 104 will register ten times, while the register 103 will not register at all. Thus, the party inspecting the reading of the meter will know that the driver of the vehicle should turn in \$25.00 or ten times 25 the flat tariff rate for one hour or a fraction thereof. If on the other hand, the meter has been in use ten times for periods of less than one hour and five times for periods over one hour, the counter 104 will register 30 fifteen times. Thus, the inspector will know that the driver should turn in \$37.50, plus whatever amount has been registered on the counter 103.

Another feature of the invention resides 35 in the provision of a shutter device for normally closing the windows 9 on the face plate 4 of the device and also while the register disks are being reset. This device essentially includes a shutter member 112, 40 which extends across the entire face of the device, and is slidably mounted as indicated at 113 on the vertical guide rods 114. In the normal neutral position of the apparatus this shutter 112 occupies a position which 45 obscures the register disks. To effect the movement of the shutter member 112, when the device is brought into use, the same is connected at its lower edge as indicated at 115 with a lever arm 116 rigidly carried on 50 the end of a shaft 117 in the frame work of the apparatus and extending longitudinally of the casing, as will be observed from Figs. 2, 3 and 4. This shaft 117 has connected to its end opposite the link 116 a link 118 which 55 connects with a pin 119 carried by the lower end of the arm of the angular lever 86 which operates the yoke 82. Therefore, when the flag is in its lowest position and the apparatus is in view the pin 119 will swing 60 the link 118 in the direction of the arrow in Fig. 5 to lower the shutter member 112. This same movement of the lever 86 swings the yoke 82 on its pivot 83 so that the register shaft 75 is pulled outwardly so that the 65 register disks 6, 7 and 8 are free to rotate thereon. When the flag lever is moved back to its neutral position the cam 36 moves the arm 87 which is connected with the arm 86 so that the link 118 of the shaft 117 is moved in the opposite direction to that shown by 70 the arrow in Fig. 5 to lift the shutter member 112 and thereby cover the windows 9 from which the register disks are visible.

From the foregoing description of parts 75 it will be clear that the normal condition of the device is when the flag F is raised so that the shank thereof which connects with the shaft 25 is in a vertical position. When the device is brought into use the flag is swung through an arc of 180°, thereby shifting the 80 clutch pinion 14 on the main transmitting shaft 13 into engagement with the gear 28 of the cam unit U. Thus immediately upon the flag being moved from its normal position the clock work of the time mechanism 85 T operates the cam unit U through the pinion 14.

The turning down of the flag lever also 90 rotates the shaft 25 so that the cam 29 releases the arm 52 of the restraining device D, thus permitting the arm 48 of said device carrying the pivot dog 46, to move upwardly so that the head of the latter bears against the periphery of the collar 39. In this state of the apparatus the levers 49 and 95 50 are held out of engagement with the cams 37 and 38 by the member 51 carried by the arm 48 of the restraining device D. Thus in this position, the cam unit U operates for 100 one hour, during which period the head of the pivot dog 46 rides along the external face of the collar 39. Immediately upon the expiration of the hour, the dog 46 passes through the clearance notch 40 into the center of the collar 39, thus permitting the 105 spring tensioned arm 48 of the restraining device D to rise and release the levers 49 and 50 so that the pawl ends thereof contact with the working edges of the cams 37 and 38, respectively.

Upon the expiration of fifteen minutes 110 the cam 37 will actuate the lever 49, which through the link 56 and pawl 69 will rotate the register disk 6 of the cents units of the apparatus. In the meantime, the pawl end of the lever 50 has been riding against the working edge of the cam 38, and owing to the special relation of the cam projections on the cams 37 and 38, the lever 50 will operate in conjunction with the lever 49 at certain intervals to cause both the disks 6 and 7 to operate to give a combined dollars and cents registration. The peculiar arrangement of numbers on the register disk 6 makes the correct total registration always 115 possible between the disks 6 and 7. That is to say, owing to the uneven amount of the fixed tariff rate that each quarter hour represents, it would be impossible to obtain the correct total with the numbers on the disk 120 130

arranged in numerical succession. However, with the arrangement specified the two disks will always operate in proper synchronism to give the correct total fare combination.

- 5 The disk 8 may be a duplicate of the disk 7 as far as the numerical succession of numbers on the periphery thereof is concerned, since the part of the disk 8 in the total fare registration is merely an ordinary pickup 10 movement from one disk to another, for each single revolution of the controlling disk, in this case the disk 7. Although the numbers on the disks 7 and 8 are in numerical succession from 1 to naught the initial arrangement thereof is such that the disk 8 will be two numbers behind the disk 6, so that when the latter disk is visible through its window 9 to show the "2" which is a part of the fixed tariff rate, the dollars disk 8 15 will register a naught. With the arrangement described it will be apparent that the register mechanism will register indefinitely in increments of \$.60 each from \$2.50 up, to the limit of the disks 6, 7 and 8 which 20 in the present instance is \$99.90.

When the shaft 25 is turned so that the flag is in its downward position it will also be clear that the cam 36 releases the arm 37 of the angular lever 86 so that the same 25 will operate under the ends of the spring 39 and thereby move the yoke 82 on its pivot to draw the shaft 35 from the register disks 6, 7, and 8 to thus permit them to freely 30 rotate. This same movement of the lever 35 causes the shutter 112 to fall so that the initial fare registration is visible to the occupant of the vehicle. During the period of 35 operation it will also be clear that the counters 103 and 104 are in operation to keep 40 check on the totals computed by the register mechanism.

When the occupant of the machine is finished with the use of the same, the driver thereof returns the flag from its downward 45 position to its normal neutral position, and the register mechanism is reset, since the cam 36 bears on the arm 87 of the lever 86 to counteract the force of the spring 39 thus shifting the yoke 82 on its pivot 83 so 50 that the shaft 75 is pushed inward and the lugs 77 thereof engage the inclined faces of the bushings 78. This same movement of the shaft causes the cam 24 to pull the clutch pinion 14 out of engagement with the gear 55 29 through the connections already described while the cam 29 presses down on the arm 52 of the restraining device to thus pull the arm 48 downward and snap the pivot trip dog 46 over the inclined inner edge of the 60 collar 39 and place the same in its normal position, while at the same time the member 51 carried by the arm 48 causes both of the levers 49 and 50 to move downward against the tension of their springs S so that 65 they are held out of contact with the cams 37

and 38. The shutter 112 is also moved behind the openings 9 in the face plate by means of the connections already described, and the entire apparatus is in condition for further service.

70

Without further description, it is thought that the many features and advantages of the invention will be readily apparent, and it will, of course, be understood that various changes in the form, proportion, and minor 75 details of construction may be resorted to without departing from the spirit of the invention or scope of the appended claims.

75

I claim:

1. A taximeter including a time mechanism, a register mechanism including a plurality of independently rotatable registering elements, and a charge regulating device adapted to actuate said registering elements an amount prime to the radix including any necessary transfer.

80

2. A taximeter including a time mechanism, a register mechanism, and a charge regulating device including means for simultaneously effecting a necessary transfer, adapted to augment the register reading an amount prime to the radix by a single step.

85

3. A taximeter including a time mechanism, a register mechanism including a plurality of independently rotatable registering elements and a charge regulating device including a plurality of differential cam elements adapted to actuate said registering elements an amount prime to the radix including any necessary transfer, and separate lever connections between said cam elements and said independently rotatable registering elements.

90

4. In a taximeter, a registering mechanism including a plurality of independently rotatable registering elements and a charge regulating device including a plurality of differential cam elements adapted to actuate said registering elements an amount prime to the radix including any necessary transfer, an actuator for said charge regulating device, and means operated by said cam elements for actuating said independently rotatable registering elements.

105

5. In a taximeter, a registering mechanism including a plurality of independently rotatable registering elements, and a charge regulating device including a plurality of differential cam elements adapted to actuate said registering elements an amount prime to the radix including any necessary transfer, an actuator for said charge regulating device, separate levers operated by said cam elements and having operative connections with said independently rotatable registering elements, and a restraining device for controlling the engagement and disengagement of said separate levers with said cam elements.

110

115

120

125

130

6. A taximeter including a time mechanism, a register mechanism, a charge regulating device actuated solely by said time mechanism, operative connections between 5 said charge regulating device and said register mechanism, a manually operated shaft having means for controlling said connections, a clutch element associated with said time mechanism, a winding shaft for said time mechanism, and means shiftable on 10 said winding shaft and operated by said manually controlled shaft to cause said clutch to connect the time mechanism with the charge regulating device.
- 15 7. A taximeter including in combination with a register mechanism, a time mechanism, a charge regulating device operated solely by the said time mechanism to actuate 20 said register mechanism, a clutch device actuated by said time mechanism, a winding shaft for said time mechanism, a clutch shifting element carried by said shaft, and means for moving said clutch shifting element to throw said clutch of the time 25 mechanism into and out of engagement with the charge regulating device.
8. A taximeter including a time mechanism, a registering mechanism including a plurality of independently rotatable registering elements, a charge regulating device, 30 adapted to actuate said registering elements an amount prime to the radix including any necessary transfer, said device consisting of a pair of differential cam elements operated 35 by the time mechanism, and register operating levers and connections operatively engaging each of said differential cam elements, a restraining device for holding said levers out of engagement with the cams, 40 manually controlled means for initially releasing the restraining device into operative relation to said charge regulating device, and means carried by said charge regulating device for delaying the engagement of 45 said levers with the differential cam elements for a predetermined time period.
9. A taximeter including a time mechanism, a registering mechanism including a plurality of independently rotatable registering elements, a charge regulating device including a plurality of differential cam elements adapted to actuate said registering elements an amount prime to the radix by single step, an operating gear, lever connections between said cams and the registering elements, a clutch associated with the time mechanism and adapted to mesh with said operating gear of the charge regulating device, and means for manually shifting 55 said clutch into and out of engagement with said gear.
10. A taximeter including a time mechanism, a registering mechanism including a plurality of independently rotatable registering elements, a charge regulating device 60 for said mechanism, including a plurality of differential cam elements adapted to augment the register reading an amount prime to the radix by a single step, an operating wheel, and a notched trip collar, a clutch 70 driven directly by said time mechanism, and means for shifting said clutch into and out of engagement with the operating wheel of said charge regulating device.
11. A taximeter including a time mechanism, 75 a registering mechanism including a plurality of independently rotatable registering elements, a charge regulating device including a plurality of differential cam elements operated by the time mechanism, 80 a manually operated shaft, a clutch for connecting said time mechanism and charge regulating device, means carried by said shaft for shifting said clutch, and register operating levers operatively connecting said 85 cams of the charge regulating device with the registering elements whereby the reading of the latter is augmented by a single step, and a restraining device controlled by said manually operated shaft for maintaining said levers out of contact with said 90 cams when the shaft is in neutral position.
12. A taximeter including a time mechanism, a register mechanism including disconnected counting members, and a time 95 controlled charge regulating device having a plurality of differential register operating elements, and a separate operating connection between each operating element and certain of the separate counting members. 100
13. A taximeter including a time mechanism, a registering mechanism including a plurality of independently rotatable registering elements, and a charge regulating device, adapted to actuate said registering 105 elements an amount prime to the radix including any necessary transfer, said charge regulating device including a plurality of differential cam elements, a notched trip collar and a driving wheel, and a resetting 110 device for said charge regulating device.
14. A taximeter including a time mechanism, a registering mechanism including a plurality of independently rotatable registering elements, and a charge regulating device adapted to actuate said registering elements an amount prime to the radix including any necessary transfer, said charge regulating device including a shaft, a charge regulating unit rotatably mounted thereon 115 and consisting of a plurality of differential cams arranged in fixed relation, a notched trip collar and a driving wheel, and also including a pinion and check disk, a spring actuated resetting segment adapted to engage with said pinion, and a check pawl for engaging with said disk. 120
15. In a taximeter, the combination with a face plate having windows therein, of separate rotatably mounted disks respec- 125 130

tively having on half of their area the signals "Recording" and "Not recording," while the other half is blank, shaft and sector means for operating said disks whereby the same alternately present their blank surface or their signal surface, and a manually controlled cam shaft having means for actuating said means for operating the disks.

16. In a taximeter, the combination with a face plate having windows therein, of separate disks respectively having on half of their area the signals "Recording" and "Not recording," while the other half is blank, separate means for operating said disks comprising spring-tensioned shafts having means at one end for engaging said disks and an arm at the other end, and a manually controlled shaft having cam means for alternately engaging said arms of said separate shafts to alternately cause said disks to present their blank and lettered surfaces.

17. A taximeter including a time mechanism, a registering mechanism, including a plurality of independently rotatable registering elements, a charge regulating device including a trip collar, and cam actuated lever elements adapted to augment the registering reading an amount prime to the radix by a single step, a restraining device normally depressing said cam actuated lever elements, manually operated means for causing said restraining device to be controlled for a predetermined period by the trip collar of the charge regulating device, said collar having means for automatically releasing the restraining device to permit the engagement of the lever elements by the cams of said charge regulating device.

18. A taximeter including a time mechanism, a register mechanism, a charge regulating device including a pair of differential cam elements and operated by said time mechanism, separate register operating levers and connections actuated directly by one of the cams of said charge regulating device, a restraining device including separate spaced arms rigidly connected and having the same axis, means carried by one of said arms for engaging said register operating levers and also having means for engaging the charge regulating device, and manually controlled means for engaging the other arm of said restraining device and adapted to initially release the same into operative relation to said charge regulating device, and means carried by said charge regulating device for delaying the working engagement of said register operating levers with said cam elements.

19. A taximeter including a time mechanism, a register mechanism, a charge regulating device including a pair of differential cam elements and operated by said time

mechanism, a shaft mounted at one side of the charge regulating device, separate register operating levers loosely mounted on said shaft and operatively connected with said register mechanism, said levers separately engaging one of said cam elements, a restraining device also mounted on the same shaft with said levers and having spaced arms, means carried by one of said arms for engaging said levers, and manually controlled means for engaging the other of said arms to control said charge regulating device.

20. A taximeter including a time mechanism, a register mechanism, the charge regulating device including a duplex cam unit and a trip member having a notch, register operating means, a restraining device having levers for maintaining said register operating levers out of engagement with the cam unit of the charge regulating device, a trip dog carried by said restraining device, manually operated means for causing said trip dog of the restraining device to come into operative engagement with the collar carried by the charge regulating device and remaining in operative relation thereto for a predetermined period while maintaining the register operating means disengaged from the cam unit, said trip dog entering the notch of the collar at the end of said predetermined period and causing said register operating levers to become engaged with the duplex cam unit to operate the register mechanism, and said manually operated means adapted to restore the restraining device to normal position and simultaneously reset the register mechanism.

21. In a taximeter, the combination of a time mechanism, a register mechanism including a plurality of independently rotatable registering elements, a charge regulating device including a duplex cam unit, a shaft, a separate operating connection between each of said cam elements of the charge regulating device and certain of said registering elements, said operating connections including levers mounted on said shaft, a register checking counter, and means carried by said shaft and operated by said levers for operating the register checking counter.

22. A taximeter including a time mechanism, a register mechanism, a charge regulating device including separate rigidly connected cam members, a notched trip collar rigid with said cam members, means for automatically maintaining said collar in normal position, register operating means, and a restraining device including a pivoted trip dog and means for maintaining said register operating means out of engagement with said cam members, and manually controlled means for releasing said restraining device whereby the trip dog bears against

- the periphery of the collar for a predetermined period, and then passes through the notch to cause the engagement of the register operating means with the cam members, said manually operated means adapted to reset the restraining device to cause the disengagement of the register operating means with the cam members and simultaneously reset the register mechanism.
23. A taximeter including a time mechanism, a register mechanism, a charge regulating device comprising a plurality of rigidly connected cam members, a collar having a notch rigidly carried by one of said cam members and an operating gear, a manually shiftable clutch member for connecting the time mechanism, with said gear of the charge regulating device, register operating means, a restraining device having a pivoted trip dog and means for holding said register operating means out of engagement with said cam members, and manually operated means for releasing said restraining device to permit the trip dog thereof to bear against the periphery of the collar and simultaneously connect the charge regulating device and the time mechanism, said trip dog being adapted to bear against the periphery of the collar for a predetermined period, during which time the register operated means are out of engagement with the cam members.
24. A taximeter including a time mechanism, a register mechanism, a charge regulating device comprising rigidly connected cam members, a collar having a notch rigidly carried by one of said cam members and an operating gear, a manually shiftable clutch member for connecting the time mechanism with said gear of the charge regulating device, registering operating means including separate register operating levers respectively for said separate cam members, a restraining device having a pivoted trip dog and means for holding said levers out of engagement with the cam members of the charge regulating device, manually controlled means for releasing said restraining device into engagement with the trip collar, pawl and ratchet means for the register mechanism, and link connections between said levers and said pawl and ratchet means.

In testimony whereof I hereunto affix my signature in the presence of two witnesses.

CHARLES DONAT RICHARD.
